CLOTH LAYING MACHINE

Maximilian Breth, Ozone Park, N. Y.

Application February 11, 1938, Serial No. 190,018

19 Claims. (Cl. 270—31)

This invention relates to cloth laying machines.

In the usual cloth laying machine, a carriage carrying a bolt of cloth is reciprocated back and forth on a cloth laying table provided with grippers at the ends thereof, to grip the layers of cloth at the folds as the carriage moves, the cloth pulling on the grippers during such operation to unwind or unroll the cloth from the bolt. It has been found that certain light weight textiles are

stretched or injured when laid with a machine of this kind. It is therefore an object of this invention to provide a machine having means to lay the cloth without injury or damage to the cloth during the laying operation, whereby the cloth

may be laid on the table without the necessity for anchoring the cloth at the folds and hence eliminating the grippers.

Another object of this invention is to provide in a machine of the character described, means to continuously feed the cloth from the bolt between rollers frictionally engaging the cloth, as the carriage reciprocates on the table.

Still another object of this invention is to provide in a machine of the character described, means for tamping down the cloth with weights at the folds during the cloth piling operation.

Yet another object of this invention is to provide in a machine of the character described, highly improved means for guiding the cloth as it is fed onto the table, including a pair of spaced rollers between which the cloth passes, which is adapted to contact the cloth when the carriage moves in one direction, and the other of which is adapted to contact the cloth when the carriage moves in the opposite direction, and including means to rotate said spaced rollers continuously to facilitate laying of the cloth, means being further provided to adjust the vertical height of said pair of spaced rollers as the cloth piles up so as to be disposed directly above the top layer.

A further object of this invention is to provide a strong and durable machine of the character described, which shall be relatively inexpensive to manufacture, easy to operate and adjust, and which shall yet be practical and efficient to a high degree in use.

Other objects of this invention will in part be obvious and in part hereinafter pointed out. The invention accordingly consists in the features of construction, combinations of elements, and arrangement of parts which will be exemplified in the construction hereinafter described, and of which the scope of application will be indicated in the following claims.

In the accompanying drawings, in which is shown one of the various possible illustrative embodiments of this invention,

Fig. 1 is a side, elevational view of a machine embodying the invention;

Fig. 2 is a cross-sectional view taken on line 2—2 of Fig. 1;

Fig. 3 is a cross-sectional view taken on line 3—3 of Fig. 1;

Fig. 4 is an enlarged, elevational, cross-sectional view of the machine embodying the invention;

Fig. 5 is a cross-sectional view taken on line 5—5 of Fig. 4;

Fig. 6 is a cross-sectional view taken on line 6—6 of Fig. 4;

Fig. 7 is an enlarged, cross-sectional view taken on line 7—7 of Fig. 2;

Fig. 8 is a partial, elevational view of a portion of my improved machine;

Fig. 9 is a cross-sectional view taken on line 9—9 of Fig. 8.

Referring now in detail to the drawings, 10 designates a cloth laying machine embodying the invention. The same comprises a cloth laying 25 table 11. Attached to one side of the table 11 and parallel to an edge thereof, is an elongated rail member 12. Clamped to spaced portions of the rail 12 are vertical upstanding similar symmetrically disposed stop members 14, 14a formed 30 with curved edges 15 on the inner sides thereof, for the purpose hereinafter appearing.

Each stop member 14, 14a has a portion 14b contacting the upper edge of the rail 12 and the top of the adjacent portion of the table 11, and formed with a vertical screw threaded opening 14c on the underside thereof. Extending from member 14 is a downwardly extending arm 14d contacting the outer surface of the rail 12, and provided with a foot 14e engaging the under-edge of said rail, and formed with an opening receiving a bolt 14f passing through the space between the rail and the table and engaging the threads of the opening 14c. A set screw 14g screwed to the arm 14d engages the outer surface 45 of the rail 12 to prevent accidental shifting of the stop member.

Mounted on said table 11 for reciprocation is a carriage 17 comprising a pair of aligned substantially similar parallel side frames 18, 18a, 50 each formed with a pair of spaced, parallel, downwardly extending legs 19 and an upwardly extending wall 20. The frame portions 18, 18a are interconnected by a plurality of horizontal cross bars 18b. The legs 19 on one side frame 55

carry wheels 21 formed with peripheral grooves 22 receiving the upper edge of the track 12. Said wheels are adapted to strike against the curved surfaces 15 of the stops 14, 14a to limit the travel of the carriage in opposite directions. The length of travel of the carriage may be adjusted by shifting the stop members.

The legs 18 on the other side frame 18 carry shafts 24, on which are rotatably mounted wheels 25. Each wheel 25 comprises a member 26 having a peripheral portion 27 of concave transverse cross-section, and a member 28 attached thereto for adjustment toward and away therefrom by screws 28a, and likewise having a peripheral portion 29 of concave transverse cross-section, opposed to the portion 27 and forming therewith an annular groove for receiving an annular tire 31 contacting the top of table 11. Extending from the member 28 of one the wheels 31, is an annular coaxial sprocket wheel 32, for the purpose hereinafter appearing.

Extending upwardly from the frame portions 18, 18a are arms 34 adapted to rotatably carry a bolt of cloth 35 to be laid or piled on the table.

25 Journalled on the walls 20 of the frame members 18, 18a is a horizontal transverse rod 36 carrying a sleeve or roller 37 of rubber or other compressible or soft, resilient material. The walls 20 are furthermore formed with horizontal slots 38, in which are slidably mounted blocks 39, in which is journalled a transverse cross shaft 40. On said shaft 40 is a sleeve or roller 41 likewise made of rubber or other compressible material, and normally in frictional contact with the sleeve 38 or roller 37.

Means is provided for adjustably pressing the roller 41 towards the roller 37. To this end, there is fixed to the inner side of each wall 20, a lug 20a formed with a screw threaded horizontal through opening 20b. Slidably mounted in each opening 20 is a pin 43 provided with a head 44 at one end formed with a semi-annular notch 44a engaging the shaft 40. Screwed within each opening 20b is a screw 45 adapted to abut the pin 43 for moving the shaft 40, when said screw is rotated in one direction, whereby the roller 41 may be pressed against the roller 37. It will be noted that the shafts 36 and 40 are at the same level in parallel relation to one another.

50 The cloth 35a from the bolt 35, may be passed between the rollers 37, 41. Means is provided for continuously rotating said rollers in the same direction for continuously feeding the cloth from the bolt forwardly, as the carriage is reciprocated back and forth and controlled by movement of the carriage, whereby the cloth may be laid or piled on the table 11 back and forth in layers of equal length during said reciprocation. To this end, shafts 36 and 40 carry pinions 36a and 40a at adjacent ends, preferably located at the front of frame member 18. The pinions 36a and 40a are spaced from one another as shown in Fig. 8 of the drawings.

65 Journalled in the walls 20, below and between the shafts 36 and 40, is a transverse shaft 47. Carried by the shaft 47 is a pinion 47a spaced from said pinions 36a and 40a, and disposed between and below said pinions.

Pivoted on said shaft 47 mediateley the ends thereof, and disposed adjacent the pinion 47a, is a lever rocker 50, on which are journalled a pair of pinions 51 and 52 spaced from one another, and meshing with the pinion 47a and located on opposite sides of said shaft.

75 As shown in Fig. 8, the pinion 51 is in mesh

not only with the pinion 47a but also with the pinion 36a. When the shaft 47, and hence the pinion 47a is rotated in a clockwise direction, looking at Fig. 8 of the drawings, pinions 51, 52 and lever 50 are rotated about shaft 47 in a clockwise direction until pinion 51 meshes with pinion 36a which will then be rotated in a clockwise direction for feeding the cloth 35a downwardly between the rollers 37, 41. However, should the shaft 47 be rotated in an opposite direction or counterclockwise, the rocker 50 and pinions 51, 52 will be swung in a counterclockwise direction about said shaft to unmesh the pinion 51 from the pinion 36a and move the pinion 52 into mesh with the pinion 40a, whereby to rotate the roller 41 in a counterclockwise direction and continue to feed the cloth 35a downwardly between the rollers 37, 41.

Means is provided to retain the rocker arm in horizontal position with both pinions 51, 52 out of engagement with respect to the pinions 36a and 40a. To this end, as shown in Figs. 8 and 9, the wall 20 of frame 18 is formed with a horizontal through opening 20c, located at a level between the shafts 47 and 36, 40, and adjacent one edge of said wall. Rocker arm 50 is formed with a through opening 50a. Extending through the opening 50a is a pin 50b, provided with a head 50c. The pin 50b may be inserted into the opening 20c when the rocker is brought to horizontal position, to retain the pinions 51 and 52 out of engagement with respect to the pinions 36a and 40a. The rocker arm may be provided with a spring pressed detent 50d adapted to engage within a groove 50e in the pin 50b to hold the pin against accidental shifting.

Means is provided for rotating shaft 47 in opposite directions as the carriage rolls back and forth on the table. To this end, shaft 47 carries a sprocket wheel 55 aligned with the sprocket wheel 40 and connected thereto by a chain 56.

It will now be understood that as the carriage moves to the right, looking at Fig. 4, shaft 47, and hence pinion 47a, will be rotated in a clockwise direction. When the carriage strikes the stop 14 at one end and begins to move in the opposite direction, the direction of rotation of wheel 31 reverses, whereby to rotate the shaft 47 in the opposite direction when the carriage is moved back.

It will now be understood that the pinion 47a rotates in opposite directions as the carriage moves back and forth, whereas the cloth 35a is fed continuously downwardly to pile the cloth on the table.

The length of cloth fed between the rollers 37, 41 should be substantially equal to the length of travel of the carriage 17. The outer diameter of the tire 31 is therefore so dimensioned with respect to the diameters of the rollers 37, 41 to substantially feed a length of cloth equal to the length of travel of the carriage in opposite directions. Fine adjustment however may be obtained by tightening or loosening the screws 28a to squeeze or relieve the tire 31 for increasing or decreasing the outer diameter thereof. Further adjustments may be made by adjusting the screws 45 which cause the roller 41 to press against the roller 37 flattening the adjacent surfaces thereof to slightly vary the length of cloth fed between said rollers.

Means is provided to guide the cloth 35a fed downwardly between the rollers 37, 41 toward the table, to facilitate piling of the cloth. To this end, there is fixed to the inner surfaces of the 75

frame members 18, 18a aligned, similar symmetrically disposed brackets or straps 60 forming therewith vertical slots to slidably receive a pair of aligned vertical similar racks 61, each formed with gear teeth 62 adjacent one longitudinal vertical edge thereof.

5 Rotatably mounted on the frames 18, 18a is a transverse horizontal shaft 60a carrying a pair of pinions 61a, meshing with the gear teeth 62 of the racks 61. Pivoted to the frame 18 is a lever 61b having a pawl 61c engaging the adjacent pinion 61a and held in engagement therewith by tension springs 61d. The lever 61b has a handle portion 61e projecting above the frame 18, where- 10 by said lever may be rotated to disengage the pawl 61c from the pinion 61a. The rod 60a carries a knob 62a which may be grasped by the operator and rotated, for rotating the pinions 61a (when the pawl 61c is released) to either raise 15 or lower the racks 61.

20 Each rack 61 is provided with a head 63 at the lower end thereof. Journalled on the ends of the heads 63 are a pair of parallel horizontal, spaced, transverse shafts 64 and 65 carrying 25 rollers 66 and 67, respectively.

The cloth 35a fed downwardly between the rollers 37, 41, passes between the rollers 66 and 67. When the carriage moves to the right, the cloth contacts the roller 66 to lay the cloth in one 30 direction, and when the carriage moves to the left, the cloth contacts the roller 67 to lay the cloth in the opposite direction.

35 As the cloth piles up the knob 62a is rotated to lift the racks to keep the rollers 66 and 67 just above the pile of cloth.

40 Means is provided to facilitate laying of the cloth by rotating the roller 66 continuously in a clockwise direction, and the roller 67 continuously in a counterclockwise direction, looking at Fig. 4 of the drawings. To this end, there is fixed to the shafts 64 and 65, sprocket wheels 68 and 69. Carried by the shaft 36, and adjacent the frame 18a, is a sprocket wheel 70. Extending downwardly from the frame 18a is an extension 71 carrying a sprocket wheel 72 disposed directly beneath and between the sprocket wheels 68 and 69. Extending about the sprocket wheels 68 and 70 and around the roller 72, is a sprocket chain 75, having a portion passing between the sprocket 45 wheels 68 and 69 and contacting the latter.

50 As the shaft 46 rotates continuously in a clockwise direction, looking at Fig. 4, sprocket wheel 69 will be rotated continuously in a counterclockwise direction, and sprocket wheel 68 will be rotated continuously in a clockwise direction. The rollers 66 and 67 will rotate continuously in a clockwise and counterclockwise direction respectively, to feed the cloth 35a whenever the cloth 55 is in contact with either one or the other of said 60 rollers.

The direction of rotation of the rollers 66 and 67 will not be altered upon raising the racks 61, as the sprocket wheels 68 and 69 will continue in engagement with the chain 75 in all vertical 65 positions of the rollers 66 and 67.

70 As the carriage 17 moves back and forth, the cloth will be laid back and forth on the table in a pile forming folds at the ends of the lay, as clearly illustrated in Fig. 1 of the drawings.

75 Means is provided to tamp the cloth down adjacent the folds each time the direction of the carriage is reversed. To this end, there is journalled on each end of the carriage 17, a transverse, horizontal cross rod 80. Fixed to each rod 80 is an upwardly extending arm 81 pro-

vided with a horizontal handle 82 at its upper end. Extending from the arm 81 are a pair of parallel, spaced fingers 82a carrying aligned adjustable screws 83.

Integrally formed with each member 18 is a lug 5 82 disposed between each pair of fingers 82a, and adapted to be engaged by the screws 83 to limit the angle of oscillation of the arm 81 and shafts. There is furthermore fixed to the ends of each rod or shaft 80, a pair of spaced, outwardly ex- 10 tends arms 88, each formed with a semi-circular notch 89 at the outer end thereof.

15 Releasably carried by the pairs of arms 88 are similar tamping mechanisms 90, 90a, adapted to rest on the table when released. Each mechanism 90, 90a comprises a pair of spaced vertical stanchions 91, each having a base 92 adapted to contact the table. The stanchions 91 are adapted to be disposed on opposite sides of the cloth laid on the table 12. Each stanchion 91 has ratchet 20 teeth 92 on the inner edge thereof. Said stanchions are interconnected at the top by a transverse horizontal cross bar 93 adapted to be received within the semi-circular notches 89 in the 25 arms 88.

30 Slidably carried by the stanchions 91 of each mechanism 90, 90a, is a transverse member 94 having a flat horizontal weighted portion 95, the lower corners whereof are curved as at 96. At the ends of each portion 95 are portions 98 35 formed with vertical slots receiving the stanchions 91. Journalled on said portions 98 is a transverse shaft 99 carrying a pair of pawls 99a adapted to engage ratchet teeth 92 of said stanchions 91. The teeth 92 are so arranged as to 35 permit the member 94 to be moved upwardly, but holding said member against downward movement except upon swinging the pawls away from the teeth.

35 In Fig. 1 of the drawings, mechanism 90 is 40 shown in position adjacent one end of the pile of cloth with the weighted portion 95 resting on the cloth to tamp down the folded ends thereof. The carriage 17 however is at the left end of its movement, and the arms 88 at the 45 right end are not in engagement with the mechanism 90 which rests on the table. Mechanism 90a however is spaced from the cloth, and is carried by the arms 88 at the left end of the carriage. The carriage may be moved from the 50 position of Fig. 1, to the right, the handles 82 being grasped by the operator to move the carriage. Mechanism 90a is lifted, as illustrated, and carried along with the carriage until the arms 88 at the right pick up the mechanism 90. 55 The carriage continues moving to the right until the portion 94 of mechanism 90a, moves onto the left end of the pile of cloth. The arms 88 at the left of the carriage are then released from the cross bar 93 of mechanism 90a, and 60 the carriage continues moving to the right while still carrying mechanism 90, until the wheel 21 strikes the stop member 14. The carriage then begins to move to the left carrying the mechanism 90 toward the left, said carriage picking 65 up the mechanism 90a and again depositing the mechanism 90 on the pile of cloth.

65 It will be noted that the shafts 80 have limited rotation to permit the mechanisms 90, 90a to be lifted up to be carried with the cloth or 70 dropped down to the table and disengaged.

75 It will be further understood that the members 94 are lifted step by step upwardly as the cloth piles up. The portions 95 thereof slide onto the pile of cloth causing said members 94 75

to be lifted, said members being held in lifted position by the bars 99 engaging the ratchet teeth 92.

It will thus be seen that there is provided a device in which the several objects of this invention are achieved, and which is well adapted to meet the conditions of practical use.

As various possible embodiments might be made of the above invention, and as various changes might be made in the embodiment above set forth, it is to be understood that all matter herein set forth or shown in the accompanying drawings is to be interpreted as illustrative and not in a limiting sense.

Having thus described my invention, I claim as new and desire to secure by Letters Patent:

1. In cloth laying apparatus, a pair of members arranged for free longitudinal reciprocation, one relative to the other for varying distances, means for limiting relative movement between said members in opposite directions, means on one of said members to support a bolt of cloth, and means controlled by relative movement between said members varying distances, in opposite directions for continuously feeding cloth from said bolt in the same direction onto said other member.

2. In cloth laying apparatus, a table, a carriage mounted thereon for reciprocation, for varying distances in opposite directions, adjustable means to limit the extent of movement of said carriage in opposite directions, means on said carriage to support a bolt of cloth, and means controlled by movement of the carriage on the table in opposite directions for continuously feeding the cloth from said bolt in one direction onto said table.

3. In apparatus for laying cloth, a table, a wheeled carriage on said table and adapted to be freely rolled back and forth thereon varying distances in opposite directions, means on said carriage to support a bolt of cloth to be laid in layers on the table, a pair of parallel rollers on said carriage and adapted to frictionally receive the cloth from said bolt therebetween, and means actuated upon reciprocation of the carriage on the table in opposite directions, varying distances, for continuously feeding the cloth between the rollers in the same direction onto said table.

4. In apparatus for laying cloth, a table, a wheeled carriage on said table and adapted to be rolled back and forth thereon, stop means to limit movement of the carriage in opposite directions, means on said carriage to support a bolt of cloth to be laid on the table, a pair of parallel rollers on said carriage and adapted to frictionally receive the cloth from said bolt therebetween, means actuated upon reciprocation of the carriage on the table for continuously feeding the cloth between the rollers in the same direction, means mounted on said carriage for vertical adjustment, a pair of spaced rollers carried by said means, the cloth fed by the first pair of rollers being adapted to pass between said second pair of rollers, and means for adjusting said means vertically.

5. In cloth laying apparatus, a table, a carriage mounted thereon for reciprocation, means on said carriage to support a bolt of cloth, stops clamped to said table for limiting reciprocation of said carriage in opposite directions, a wheel on said carriage engaging said table, a transverse shaft on said carriage, means cooperating with said wheel for rotating said shaft upon moving said

carriage on said table, a pinion on said shaft, a pair of parallel, transverse shafts on said carriage carrying rollers adapted to receive and frictionally engage cloth from said bolt, therebetween, pinions on said pair of shafts, a member pivoted to said first shaft, and a pair of pinions on said pivoted member meshing with said first mentioned pinion, as said pivoted member rotates about said shaft, one of said pair of pinions on said pivoted member being adapted to engage one of the pair of pinions on said pair of shafts, in one position of said pivoted member, and the other of the pair of pinions on said pivoted member meshing with the other of said pair of pinions on said pair of shafts, in another position of said pivoted member.

6. In apparatus for laying cloth, a table, a wheeled carriage on said table and adapted to be rolled back and forth thereon, means on said carriage to support a bolt of cloth to be laid in layers on the table, a pair of parallel rollers on said carriage and adapted to frictionally receive the cloth from said bolt therebetween, and means actuated upon reciprocation of the carriage on the table in opposite directions for rotating one roller when the carriage moves in one direction and the other roller when the carriage moves in the opposite direction.

7. In cloth laying apparatus, a table, a member mounted thereon for reciprocation, means on said member for supporting a bolt of cloth to be laid on said table, a pair of parallel rollers disposed transversely of the direction of movement of said member, adapted to frictionally receive the cloth from said bolt therebetween, pinions on said rollers, a pinion rotatably mounted on said member, means for rotating said last pinion in one direction upon moving said member in one direction, and in the opposite direction upon moving said member in the opposite direction, a member pivoted on said carriage about the axis of said last pinion and carrying a pair of pinions meshing therewith, one of said pair of pinions on said pivoted member being adapted to mesh with one of said pair of pinions on said rollers upon moving said first member in one direction, and the other of said pair of pinions on said pivoted member being adapted to mesh with said other of said pair of pinions on said rollers upon moving said first member in the opposite direction.

8. In cloth laying apparatus, a table, a member mounted thereon for reciprocation, means on said member for supporting a bolt of cloth to be laid on said table, a pair of parallel rollers disposed transversely of the direction of movement of said member, adapted to frictionally receive the cloth from said bolt therebetween, pinions on said rollers, a pinion rotatably mounted on said member, means for rotating said last pinion in one direction upon moving said member in one direction, and in the opposite direction upon moving said member in the opposite direction, a member pivoted on said carriage about the axis of said last pinion and carrying a pair of pinions meshing therewith, one of said pair of pinions on said pivoted member being adapted to mesh with one of said pair of pinions on said rollers upon moving said first member in one direction, and the other of said pair of pinions on said pivoted member being adapted to mesh with said other of said pair of pinions on said rollers upon moving said first member in the opposite direction, and means for retaining said pivoted member against rotation in such position that the pinions thereon are out of engagement with the pinions on said rollers.

9. In apparatus for laying cloth, a table, a wheeled carriage on said table and adapted to be rolled back and forth thereon, means on said carriage to support a bolt of cloth to be laid in layers on the table, a pair of parallel rollers on said carriage and adapted to frictionally receive the cloth from said bolt therebetween, means actuated upon reciprocation of the carriage on the table in opposite directions, for continuously feeding the cloth between the rollers in the same direction, and means for pressing said rollers together.

10. In apparatus for laying cloth, a table, a wheeled carriage on said table and adapted to be rolled back and forth thereon, means on said carriage to support a bolt of cloth to be laid in layers on the table, a pair of parallel rollers on said carriage and adapted to frictionally receive the cloth from said bolt therebetween, means actuated upon reciprocation of the carriage on the table in opposite directions, for continuously feeding the cloth between the rollers in the same direction onto said table, said rollers having compressible outer portions and means for causing relative movement of said rollers one toward the other.

11. In apparatus for laying cloth, a table, a wheeled carriage on said table and adapted to be rolled back and forth thereon, stop means to limit movement of the carriage in opposite directions, means on said carriage to support a bolt of cloth to be laid on the table, a pair of parallel rollers on said carriage and adapted to frictionally receive the cloth from said bolt therebetween, means actuated upon reciprocation of the carriage on the table for continuously feeding the cloth between the rollers in the same direction, means mounted on said carriage for vertical adjustment, a pair of spaced rollers carried by said means, the cloth fed by the first pair of rollers being adapted to pass between said second pair of rollers, and means for adjusting said means vertically, one of said second pair of rollers being adapted to engage the cloth when the carriage is moved in one direction, and the other of said second pair of rollers being adapted to engage the cloth when the carriage is moved in the opposite direction, and means for continuously rotating each of said second pair of rollers in the same direction in all the vertically adjusted positions of said means.

12. In apparatus for laying cloth, a table, a wheeled carriage on said table and adapted to be freely rolled back and forth thereon any distance in either direction, means on said carriage to support a bolt of cloth to be laid in layers on the table, a pair of parallel rollers on said carriage and adapted to frictionally receive the cloth from said bolt therebetween, means actuated upon reciprocation of the carriage on the table any distance in opposite directions, for continuously feeding the cloth between the rollers in the same direction, and stop means adapted to be clamped to the table in various adjusted positions for limiting movement of said carriage in various adjusted positions relative to the table in opposite directions.

13. In cloth laying apparatus, a table, a carriage mounted thereon for reciprocation, means on said carriage to support a bolt of cloth, stops clamped to said table for limiting reciprocation of said carriage in opposite directions, a wheel on said carriage engaging said table, a transverse shaft on said carriage, means cooperating with said wheel for rotating said shaft upon moving said carriage on said table, a pinion on said shaft, a pair of parallel, transverse shafts on said carriage carrying rollers adapted to receive and friction-

ally engage cloth from said bolt therebetween, pinions on said pair of shafts, a member pivoted to said first shaft, and a pair of pinions on said pivoted member meshing with said first mentioned pinion, as said pivoted member rotates about said shaft, one of said pair of pinions on said pivoted member being adapted to engage one of the pair of pinions on said pair of shafts, in one position of said pivoted member, and the other of the pair of pinions on said pivoted member meshing with the other of said pair of pinions on said pair of shafts in another position of said pivoted member, said wheel having a rubber tire, and means for expanding said tire on said wheel.

14. Apparatus for laying cloth on a table, comprising a carriage adapted to be freely moved back and forth on said table, varying distances in either direction, means on said carriage to support a bolt of cloth to be laid on the table, a pair of parallel rollers on said carriage adapted to frictionally receive the cloth from said bolt therebetween, and means actuated upon reciprocation of said carriage varying distances in either direction for continuously feeding the cloth between the rollers in the same direction onto said table as said carriage moves back and forth on the table.

15. Apparatus for laying cloth on a table, comprising a carriage adapted to be moved back and forth on said table, means on said carriage to support a bolt of cloth to be laid on the table, a pair of parallel rollers on said carriage adapted to frictionally receive the cloth from said bolt therebetween, means actuated upon reciprocation of said carriage for continuously feeding the cloth between the rollers in the same direction, a second pair of spaced rollers supported on said carriage, the cloth fed by the first pair of rollers being adapted to pass between said second pair of rollers, one of said second pair of rollers being adapted to engage the cloth when the carriage is moved in one direction, and the other of said second pair of rollers being adapted to engage said cloth when said carriage is moved in the opposite direction, and means for continuously rotating each of said second pair of rollers in the same direction.

16. Apparatus for laying cloth on a table, comprising a carriage adapted to be moved back and forth on said table, means on said carriage to support a bolt of cloth to be laid on the table, a pair of parallel rollers on said carriage adapted to frictionally receive the cloth from said bolt therebetween, means actuated upon reciprocation of said carriage for continuously feeding the cloth between the rollers in the same direction, a second pair of spaced rollers supported on said carriage, the cloth fed by the first pair of rollers being adapted to pass between said second pair of rollers, one of said second pair of rollers being adapted to engage the cloth when the carriage is moved in one direction, and the other of said second pair of rollers being adapted to engage said cloth when said carriage is moved in the opposite direction, means for adjusting the vertical positions of said second pair of rollers, and means for continuously rotating each of said second pair of rollers in the same direction, in all the vertically adjusted positions thereof.

17. Apparatus for laying cloth on a table, comprising a carriage adapted to be rolled back and forth on said table, means on said carriage to support a bolt of cloth to be laid on the table, a pair of parallel rollers on said carriage adapted to frictionally receive the cloth from said bolt

therebetween, means actuated upon reciprocation of said carriage on said table for continuously feeding the cloth between the rollers in the same direction, means mounted on said carriage for vertical adjustment, a pair of spaced rollers carried by said means, the cloth fed by the first pair of rollers being adapted to pass between said second pair of rollers, and means for adjusting said first means vertically, one of said pair of rollers being adapted to engage the cloth when the carriage is moved in one direction, and the other of said second pair of rollers being adapted to engage said cloth when said carriage is moved in the opposite direction.

18. Apparatus for laying cloth on a table, comprising a carriage adapted to be mounted on a table for reciprocation back and forth, means on said carriage to support a bolt of cloth, a wheel on said carriage adapted to engage said table, a transverse shaft on said carriage, means cooperating with said wheel for rotating said shaft, upon moving said carriage on said table, a pinion on said shaft, a pair of parallel transverse shafts on said carriage carrying rollers adapted to receive and frictionally engage cloth from said bolt therebetween, pinions on said pair of shafts, a member pivoted to said first shaft, and a pair of pinions on said pivoted member meshing with said first mentioned pinion, as said pivoted member rotates about said shaft, one of said pair of pinions on said pivoted member being adapted to engage one of the pair of pinions on said pair of shafts, in one position of said pivoted member, and the other of said pair of pinions on said pivoted member meshing with the other of said

pair of pinions on said pair of shafts, in another position of said pivoted member.

19. In cloth laying apparatus, a table, a member mounted thereon for reciprocation, means on said member for supporting a bolt of cloth to be laid on said table, a pair of parallel rollers disposed transversely of the direction of movement of said member, adapted to frictionally receive the cloth from said bolt therebetween, pinions on said rollers, a pinion rotatably mounted on said member, means for rotating said last pinion in one direction upon moving said member in one direction, and in the opposite direction upon moving said member in the opposite direction, a member pivoted on said carriage about the axis of said last pinion and carrying a pair of pinions meshing therewith, one of said pair of pinions on said pivoted member being adapted to mesh with one of said pair of pinions on said rollers upon moving said first member in one direction, and the other of said pair of pinions on said pivoted member being adapted to mesh with said other of said pair of pinions on said rollers upon moving said first member in the opposite direction, whereby to continuously feed cloth from said bolt between said rollers as said carriage is reciprocated on said table in opposite directions, a second pair of spaced, parallel rollers supported on said carriage, the cloth fed between said first pair of rollers being adapted to pass between said second pair of rollers, and means for rotating said second pair of rollers in the same direction.
